RUPTURE DISK ASSEMBLY

Harry Robert Spence, Jr., Nitro, W. Va., assignor
to American Viscose Corporation, Wilmington,
Del., a corporation of Delaware

Application December 27, 1948, Serial No. 67,513.

6 Claims. (Cl. 18—8)

1

The present invention relates to the production of filaments such as those obtained by forcing a filament-forming liquid through small diameter orifices.

In producing viscose rayon filaments, for example, a spinning solution of cellulose xanthate is forced through orifices ranging in diameter from 0.001 to 0.003 of an inch. The total number of such orifices may range from 40 or 50 to several thousand in a single spinneret. In service, these orifices may become wholly or partially clogged because of impurities, or imperfectly homogenized viscose spinning solution, or coagula which occasionally prematurely form in a spinning solution, or structural imperfections of the spinneret. When this condition occurs, excessive hydraulic forces are imposed upon the spinneret which may cause distortion or rupture thereof. As costly corrosion-proof materials and much labor is required for constructing satisfactory spinnerets, it is desired to keep the maintenance and the replacement cost at a minimum. Moreover, as the orifices become plugged, the diameter of the extruded filament is changed. Under the conditions when, for example, the orifices become reduced in diameter by the deposition of material on their inner walls, the diameter of the filaments is reduced. Another condition that may occur, is when some of the holes become plugged but others remain open and the filaments are extruded from the open holes under increased pressure. As the speed of the godet which withdraws the filament from the spinneret remains unchanged, these filaments are therefore larger in diameter since the volume of solution extruded per orifice is greater at increased pressure. As the godet imposes a certain desired stretch upon the filament which produces substantial elongation and reduction in denier as well as orienting of the filament cells in the filament immediately after leaving the spinneret, a substantial change in diameter of the filaments occurring as a result of the change in the condition of the spinneret, varies the degree of stretching imposed on the yarn and results in a rayon material of non-uniform and undesired characteristics.

The principal objects of the invention, therefore, are: to provide a pressure-responsive device in an extrusion apparatus for filaments, films or other articles which is sensitive to rises in pressure resulting from plugged filters, spinnerets or other types of orifice plates; to adapt such a device to present extrusion machinery; and to produce filaments of uniform denier and elongation. Other objects, features and advantages of

2

the invention will become obvious in the following description of the invention, and the drawings.

In the drawing illustrative of the invention,

Fig. 1 is a fragmentary view partly in section as seen from the side, of the filament extruding portion of a rayon spinning machine showing an embodiment of the invention;

Fig. 2 is an end view of the apparatus seen in Fig. 1;

Fig. 3 is an enlarged sectional view of a portion of the apparatus seen in Fig. 1; and

Fig. 4 is a diametrical section of a rupture plate according to the invention.

Briefly, the invention comprises providing a pressure rupturable element in a wall of any means for conducting a filament forming solution from a feed device to an orifice plate. The invention may be used on many types of filament extrusion equipment, but since the manufacturing of rayon filaments constitutes an important field of application, it will be described with respect to the making of viscose rayon yarn.

Referring specifically to Fig. 1, a portion of the rayon spinning machine is shown, wherein the spinning solution is conducted from a pump (not shown) through a conduit 8 and through a swivel connection into the filter base 11. The filter base 11 is pivotable on an axis extending from one side through a threaded screw device 9 which is adjustable within a threaded aperture extending through the bracket 13. Device 9 terminates in a round lug 10 which fits within a shallow complementary recess 16 provided for it on the side of the filter base 11. The other side of the filter base 11 is provided with a tapered recess 14 coaxial with the pivoting axis of the base, adapted for receiving a rounded and tubular insert 15. Bracket 12 is provided with a fluid-conducting passageway 17 and recesses at each end of the passageway for receiving the insert 15 and the threaded fitting 18 which connects the tube 8 to the bracket 12. By adjusting the screw device 9, the surface within recess 14 is forced tightly against the end of the insert 15 which in turn is forced tightly against the surfaces within the recess at 19. A passageway 35 extends inwardly of the filter base 11 from the recess 14 to a threaded aperture shown in Fig. 2. Solution passing through the filter base 11 flows into the filter case 20 and through a conventional filter element contained therein, and also through a curved glass tube 21 into the spinneret supported within the coupling 23 submerged within a spin bath below the indicated liquid level 24.

Fig. 3 is an enlarged sectional view of the filter

base 11 shown in Fig. 1. The body of the filter base is of a type which has been widely used in conventional rayon spinning machinery. The filter base 11 is a desirable portion of the spinning machinery to which to adapt the present invention, especially since the filter base is normally provided with a threaded aperture or recess 27. The rupture closure or disc 25 and an outer protective closure or cap 30 are held in place along an annular recess 29 within the aperture 27 by an exteriorly threaded annulus 28, the lower surface of which bears on an annular flange 31 of cap 30. Flange 31, in turn, bears on an annular flange 33 of the disc 25. Flange 33 is forced against a gasket 32 of resilient material such as vulcanized rubber composition for positive sealing of the aperture 27. The cap 30 is made of any suitable material such as metal stampings or moldable plastic material. It may be made, if desired, of a transparent plastic material such as a vinyl chloride-vinyl acetate copolymer, so that the disc may be visually inspected at any time. The cap 30 has an end wall, spaced from the disc 25 to provide a chamber therebetween, and a lateral wall extending from the end wall to the flange 31. The cap 30 is apertured preferably in the lateral wall thereof, e. g. by the aperture 34. The aperture 34 provides free communication between the outside space or atmosphere and the chamber within the cap 30 between its end wall and the disc 25 to permit the escape of solution, and deflection thereof into space not occupied by personnel, upon rupturing of the disc 25.

Disc 25 is preferably of concavo-convex plate construction. Such a disc has better structural strength and may be thinner gauge than a flat disc for opposing the hydraulic forces to which it is subjected. This construction of the disc and the fact that the inlet and outlet ducts 35 and 36 respectively have ports at opposite ends of the space or chamber 37 between the bottom of the recess 27 and the inner wall of the disc 25 causes the liquid passing through the inlet port of chamber 37 at the terminus of duct 35 to approach the inner surface of the disc at an angle and sweep along said surface until it reaches the outlet port of chamber 37 associated with duct 36. In this manner the chamber 37 is maintained free of over-aged, partially-set spinning solution and the inner surface of disc 25 is swept free of any materials having a tendency to adhere to the disc. The disc 25 may be constructed of any substantially rigid corrosion-resistant material having the required tensile strength. In the practice of the invention, a nickel-plated aluminum disc is found very satisfactory for use as a rupture disc on equipment for handling viscose solutions. For cellulose acetate solutions, stainless steel discs are satisfactory. The thickness of the disc will be dependent upon the maximum operating pressure to which it is permissible to subject the spinneret while allowing a margin of safety, and will be of the order of a few thousandths of an inch. The disc may be of such thickness that it will rupture at any predetermined increase in pressure such as that produced by a certain degree of clogging of the spinneret or the filter.

In the embodiment of the invention shown and illustrated, the rupture disc 25 was placed in a preferred position with respect to the spinneret, the filter, and the pumping means partly because it was desired to adapt the invention to existing apparatus and also because it was desired that there be means for detecting plugging

of the filter element contained in the filter case 20. Consequently in the apparatus shown, plugging of either the spinneret or the filter may result in bursting of the disc 25. However, such a rupturable element as the disc 25 may be installed in a suitable aperture therefor in the wall of any portion of the apparatus through which spinning solution may flow between a pumping means and the spinneret supported in the spinneret coupling 23.

Obviously, many changes and variations may be made in the details of the invention as specifically set forth without departing from the nature and spirit of the invention as defined in the appended claims.

I claim:

1. An extrusion machine for producing artificial films, filaments, and other articles from a liquid-to-plastic material comprising positive delivery means for the material, an orificed extrusion plate, duct means for carrying the material from the delivery means to the extrusion plate, an intermediate section of the duct means comprising a chamber having an inlet port and an outlet port spaced adjacent opposite ends of the chamber for connecting it in series with adjacent sections of the duct means, and a substantially rigid closure constituting a wall of said chamber and extending over the ports, said closure having sufficient strength to resist rupture up to but not above a predetermined pressure of the material and the extrusion plate having a strength sufficient to resist rupture exceeding said pressure, a protective cap secured in position over the closure and having a wall thereof spaced from the closure to provide a chamber therebetween, and an aperture in the cap providing free communication between the outside atmosphere and the last-mentioned chamber.

2. A machine for spinning artificial filaments comprising pumping means, a spinneret, a base, a filter, a case for housing the filter secured to the base, said base and case being connected between the pumping means and the spinneret and in series therewith, a recess in the base in series communication with the pumping means and the spinneret, a substantially rigid closure secured in the recess and being made of a strength such that it will rupture at a predetermined pressure which is less than that which the spinneret is adapted to withstand, a cap for the closure having an end wall and a lateral wall, said end wall being spaced from the closure to provide a chamber therebetween, and an aperture in the lateral wall of the cap providing free communication between the outside atmosphere and the chamber.

3. A spinning machine as defined in claim 2 wherein the spaced cap is transparent.

4. A machine for spinning artificial filaments comprising an assembly pivotable with respect to a liquid spinning solution supply means, said assembly comprising a pivotable base, a filter case attached to the base, a spinneret, conduit means for leading the spinning solution from the filter case to the spinneret, a recess in the base, a substantially rigid inner closure secured in the recess and providing an enclosed space between the bottom of the recess and the closure, an inlet duct extending through the base to one end of the space, an outlet duct extending from an opposite end of the space through the base to the filter case, said closure being rupturable at lower pressure than the spinneret, an outer closure secured in the recess and having an outer

wall portion spaced from the inner closure to provide a chamber therebetween, and an aperture in the outer closure providing free communication between the outside atmosphere and the last-mentioned chamber.

5. A machine as defined in claim 4 in which the inner closure is of concavo-convex shape with the concavity facing the bottom of the recess.

6. A machine as defined in claim 4 in which the outer closure has an end wall and a lateral wall and the aperture is provided in a lateral wall of the outer closure.
